UNITED STATES PATENT OFFICE.

JACOB S. AYDELOTT, OF COLUMBUS, OHIO, ASSIGNOR OF ONE-FOURTH TO M. M. DAVIS,
OF UHRICHSVILLE, OHIO.

WINDOW-SCREEN.

1,289,077.

Specification of Letters Patent. Patented Dec. 31, 1918.

Application filed June 8, 1918. Serial No. 238,820.

To all whom it may concern:

Be it known that I, JACOB S. AYDELOTT, a citizen of the United States, residing at Columbus, in the county of Franklin and 5 State of Ohio, have invented certain new and useful Improvements in Window-Screens, of which the following is a specification.

This invention relates to screens, and has particular reference to an improved type of 10 screen adapted for use in connection with windows, doors or the like and embodying features of construction which permit the same to assume an outwardly bulged position when operatively applied, in order that 15 one located behind the screen may readily view exterior locations in a convenient manner without necessitating the removal of the screen in order to accomplish this desired purpose.

20 The chief objection to window screens of ordinary form resides in the fact that in order for one to view exterior locations or positions, it is necessary to remove the screen from its operative position in order to look 25 out. Therefore, the present invention contemplates a screen structure which when applied will produce an outwardly bulging contour, disposed to extend some distance beyond the outer face of a window frame or 30 other similar wall opening, whereby through the provision of the outwardly bulging portion of my improved screen one may readily gaze through its foraminous mesh at a position in advance of said window frame so 35 that exterior locations may be readily viewed.

To this end, my invention comprises essentially a screen structure comprising a substantially resilient foraminated body, 40 which latter is provided along certain of its marginal edges with a plurality of strip elements, these elements being adapted to be positioned within guides formed in a window frame, whereby when the structure is 45 thus positioned the same will be outwardly bowed or flexed to extend in a secured manner beyond the outer margins of the window frame and at the same time will be fully screened to said frame.

A further object resides in the provision 50 of novel means for reinforcing the upper and lower edges of the screen and at the same time to provide means for securing the top and bottom members of the screen structure in their operative positions. 55

A still further object of the invention is to provide a screen structure which will assume the desired outwardly bulging condition when set up for use, but to be also capable of assuming a substantially flat position 60 when not in use so that a number of the same may be assembled with but minimum bulk in order to be conveniently shipped.

With these and other objects in view, as 65 will appear as the description proceeds, the invention accordingly consists in the novel features of construction, combinations of elements, and arrangement of parts herein-after fully described and having the scope 70 thereof defined by the appended claims.

In the drawing, wherein has been shown one of the preferred embodiments of the invention:

Figure 1 is a perspective view of the 75 screen comprising the present invention, and illustrating its application to an ordinary window frame,

Fig. 2 is a vertical sectional view taken through the screen and the window frame, 80

Fig. 3 is a horizontal sectional view,

Fig. 4 is a view of the screen when detached, and

Fig. 5 is a detail perspective view of one of the reinforcing strips of the screen, and 85 illustrating the outwardly struck tongues thereof.

Similar characters of reference denote like and corresponding parts throughout the several views of the drawing. 90

In the preferred adaptation of my invention, use is made of a screen structure 1, consisting of a substantially resilient foraminated body portion 2, in this instance the vertical edges of portion 2 are provided 95 with vertically extending bars 3, which latter are adapted to be positioned within the spaced sash guides 4 of an ordinary window

frame 5. It will be observed that when the structure 1 is normally positioned the same is considerably wider than the width of the frame 5, thereby in order to position the structure in operative relation with said frame it is necessary to outwardly bow or flex the body portion 2 thereof, so that the bars 3 may engage with the sides of the guides 4. From this it will be seen that the body portion 2 will extend some distance beyond the outer portions of the window frame 5, so that one may lean out of the frame 5 to view exterior conditions without disturbing in any way the applied position of the screen structure. Also, due to the inherent resiliency of the body portion 2, the bars 3 will be maintained in a secure manner within the guides 4, so that accidental displacement of the screen as a whole is effectively prevented. By the yieldable nature of the body portion 2 no difficulty will be encountered in flexing the same to assume the desired bowl contour, and when applied the screen structure automatically maintains its desired position and form. Secured to the upper and lower edges of the body portion 2 are a plurality of reinforcing strips 6 and 7 respectively. These strips are preferably formed from U shaped pieces of sheet metal and are adapted to firmly receive and clamp the upper and lower marginal portions of the screen structure. These strips firmly brace the structure 1 as a whole and serve to prevent the same from unduly bending or tearing. The upper strip 6 is provided with a series of outwardly struck, integral tongues 8, which extend inwardly and substantially flush with the upper edges of the portion 2. Adapted to rest upon these tongues 8 is a top member 10, formed from any desired material, but is preferably non-foraminous to prevent rain or the like from entering the frames 5 and hence into the interior of a building. The lower strip 7 is also provided with similar inwardly projecting lugs or tongues 11, which are apertured as at 12 for the reception of suitable fastening elements, which latter are employed to secure a foraminous bottom member 13 in its operative position within the screen structure. It is desirable that this member 13 should be formed from a foraminous material, since by use of this material a greater range of vision is afforded by the screen structure 1.

From the foregoing description it will be seen that mechanism has been provided whereby the objects of the invention have been achieved and that all of the advantageous features of construction and utility above mentioned are, among others, present.

It will be observed upon reference to Fig. 4 that when the screen structure is not in use the same will assume a substantially

flat condition, this being due to the inherent resiliency of the body portion 2, and when in this latter position the screen structure may be readily and compactly assembled with similarly constructed screens and thus stored or shipped while occupying but a minimum space. The screen is not limited to its use in connection with window frames, as the principles thereof are equally adaptable to doors and other screen like closures. By virtue of the construction described one may lean out of a window frame for a considerable distance so as to obtain a clear view of surrounding localities, yet through the provision of the curved screen structure described, the latter will interfere or limit in no way such desirable observations.

From the foregoing it is thought that the advantages and operation of the device forming the subject matter of this invention will be readily understood and, therefore, a more extended explanation has been accordingly omitted.

I claim:

1. A screen comprising a resilient foraminated body, securing strips disposed along the vertical edges of said body and adapted to be actively positioned within the guides of a window frame, whereby said body will be substantially bowed and flexed, and top and bottom members carried by said body. 90

2. A screen comprising a foraminated body, means disposed along the vertical edges of said body and arranged for resilient cooperation with the guides of a window frame by flexing and bowing said body 100 when the latter is actively positioned, and horizontally disposed means for covering the top and bottom portions of said screen.

3. A screen comprising a foraminated body, securing strips disposed along the vertical edges of said body and situated for resilient coöperative relation with the sides of a wall opening, whereby said body portion when actively positioned will be forced to assume a bowed condition and to protrude beyond said wall, reinforcing strips carried by the upper and lower edges of said body, and means for securing an opaque top member and a foraminated bottom member to said reinforcing strips. 105

4. A screen comprising a foraminated body portion, vertically disposed strips secured to the outer side of said body portion and situated adjacent to the side edges thereof, said strips being adapted for coöperation with a wall structure so as to secure the screen in a bowed and flexed condition therewith, reinforcing strips mounted upon the upper and lower edges of the body portion, tongues protruding inwardly from said strips, and top and bottom members co-operatively carried by said tongues. 120

5. A screen comprising a resilient forami-

nated body portion, vertically disposed strips carried by the vertical edges of said body and adapted to connect the latter with a wall structure, reinforcing members disposed along the upper and lower edges of said body, supporting means protruding

from said reinforcing members, and top and bottom walls connected with said supporting means.

In testimony whereof I affix my signature. 10

JACOB S. AYDELOTT.
